UNITED STATES PATENT OFFICE.

JOSEPH STOKES WILLIAMS, OF RIVERTON, NEW JERSEY.

WATERWAY REINFORCED CONCRETE CONSTRUCTION AND METHOD OF CONSTRUCTING THE SAME.

1,350,690.

Specification of Letters Patent. Patented Aug. 24, 1920.

Original application filed March 3, 1909, Serial No. 481,070. Divided and this application filed January 21, 1913. Serial No. 743,238.

To all whom it may concern:

Be it known that I, JOSEPH STOKES WILLIAMS, a citizen of the United States, residing at Riverton, in the county of Burlington, State of New Jersey, have invented a new and useful Waterway Reinforced Concrete Construction and Methods of Constructing the Same, of which the following is a specification.

10 My present invention is especially designed to be employed in constructing bulk heads, dykes, shore or levee walls, sea walls, wharfs, piers, foundations, water bed reinforcements, and all alined structures in or 15 along waterway beds and the shores, and is a division of my copending application, filed by me on the 3rd day of March, 1909, Serial No. 481,070, wherein I have broadly claimed certain methods and apparatus for establishing concrete construction in and about waterways.

20 The main object of my present invention is to decrease the cost of the construction and at the same time increase the stability and 25 efficiency thereof.

A further object of my invention is to utilize forms or molds which can be cheaply and conveniently placed and removed, which are capable of successive use, and which provide 30 large units of construction in their capacity.

35 A further purpose of my invention is to provide for the establishing of large units of construction successively and progressively along the line thereof.

40 A further purpose of my invention is to make use of guides or forms which are floated to place and adapted to be sunk or lowered to alined operative position, after 45 which they can be floated so as to be free from the construction for which they have acted as forms, and to successively use the same in the construction of other sections of the same concreting or in other work of a similar nature.

50 A further purpose of my invention is to make use of the surface or interior of a vessel for the receipt and support of the material and apparatus of which the concrete is being formed or by which the concrete is mixed or distributed.

A further purpose of my invention is to provide in a single construction, a form or guide for giving definite form and shape to

the concrete work, a working platform for receiving, mixing and distributing the same, and a dock for use of vessels supplying material.

A further purpose of my invention is to provide means for establishing wall construction in or along the bed of a waterway by means of floatable, sinkable and refloatable forms for concrete chambering and wall formation which shall be capable of continuous and repeated use, and by which excavations can be made and concrete supplied by suitable pipes or conduits through passages by which the excavation has been accomplished, whereby the excavated material may be discharged and supply of concrete be conveyed over or from a platform carried thereby.

A further purpose of my invention is to progressively excavate and fill with concrete within a subaqueous bed to a predetermined depth and level.

Other purposes and objects of my invention will more clearly appear in the detailed description hereinafter set forth.

For the purpose of illustrating my invention I have shown in the accompanying drawing different embodiments thereof which in practice will give satisfactory and reliable results, although it is of course to be understood that the various instrumentalities of which my invention consists can be variously arranged and organized and that my invention is not limited to the precise arrangement and organization of these instrumentalities as herein shown and described.

Figure 1 represents a perspective view, partially interrupted, of one embodiment of my invention.

Fig. 2 represents a perspective view of another embodiment of my invention.

Fig. 3 represents a perspective view partially interrupted, of a construction corresponding to that formed by the apparatus shown in Fig. 1.

Fig. 4 represents the construction seen in Fig. 3 as supported on reinforced walls such as are shown in Fig. 9.

Fig. 5 represents a perspective view of a floatable form provided with a removable facing element.

Fig. 6 represents a perspective view partially interrupted, of another embodiment of my invention.

Fig. 7 represents a perspective view, partially interrupted, of another embodiment of my invention.

Fig. 8 represents in section a perspective view of another embodiment of my invention.

Fig. 9 represents a perspective view, in section, showing one type of the construction.

10 Fig. 10 represents a sectional plan view of an embodiment of my invention in operative position and which is capable of forming the type of concrete construction seen in Fig. 9.

15 Fig. 11 represents a perspective view, partially interrupted, of an embodiment of my invention.

Similar numerals of reference indicate corresponding parts in the figures.

20 Referring to the drawings:

It is to be understood that when I refer to concrete, I intend the same to be broadly construed as covering a binding material of any desired nature, such as, for example, 25 cement, concrete, or grouting, and this term concrete also includes any desired forms of reinforcement thereof which may be desirable. Furthermore, in certain cases it is advantageous to employ fillers in order to materially 30 reduce the cost without decreasing the strength of the construction.

Referring now first to the construction seen in Fig. 1, 1 designates a floatable support whose under surface is grooved as 35 shown in end elevation at 2, 3 and 4 to the shape of the concrete construction which is to be formed. The contour of the under or other surfaces of the support 1 constitutes the mold or form for the concrete, and the 40 pipes or conduits 5 and 6 which provide for the operation of excavating and concrete conveying tubes or conduits by which the material of the bed may be removed to the required extent either vertically or laterally 45 or both, and by which the excavation can be filled with concrete. Although for purpose of illustration, I have shown these tubes or passageways as covering but a small portion of the top and end surfaces, it will 50 be apparent that they may be spread over as much of either surface as may be required to provide for either vertical or horizontal excavating or both vertical and horizontal excavating and feeding. 7 designates passages 55 which provide for the admission of concrete along the top 3 of the space formed by the dredging operation. Concrete can be inserted through all of these passages and the surface be made smooth and uniform by slight 60 longitudinal movement of the mold if this prove necessary in individual cases, but such longitudinal movement of the mold is not essential in every case. Reinforcements of metal can be passed through these passageways 65 prior and subsequently to concreting.

8 designates ballast pipes or water valves for the purpose of permitting water to flow into the structures, to sink them to any desired degree, and mechanism is preferably provided on the support or independent thereof for removing the water in order to refloat the support, it being apparent that any desired mechanism may be employed for this purpose.

10 In Fig. 3 I have shown a construction resulting from the operation of the device illustrated in Fig. 1 and operated by the method described and wherein it will be seen that side walls 9 and 10 are provided which are formed integrally with a connecting base 11 located on a dredged channel.

15 In the embodiment seen in Fig. 2, I have shown a construction capable of operation to form or mold a single wall of the type illustrated at 9 and 10 in Fig. 3, and in which the excavation can be made by hydraulic means through passageways 7 or through pipes or tubes corresponding to those seen at 5 and 6 in Fig. 1, but which I have not considered it necessary to illustrate in connection with 20 Fig. 2, since such construction will be clearly understood by reference to Fig. 1.

25 In both the embodiments seen in Figs. 1 and 2, the form or mold preferably remains in position after the concrete has been completely formed in order that the concrete may be properly supported while setting. In both Figs. 1 and 2, the channel in advance of the floatable mold or former may be dredged preliminarily by any desired type 30 of dredge or excavator or the structures may do their own dredging, if preferred. In both cases also in doing their own dredging they could be sunk to a lower dredging position and afterward raised to mold and finish 35 or the dredging can be done by adjustable members through the tubes, passageways or channels with molding and finishing as hereinbefore described. This raising can be accomplished by variation in ballast, by 40 separate mechanical means or by closing the passages 7 and putting pressure on the concrete and the bed.

45 In the embodiment seen in Fig. 7 I have shown two floatable structures 12 which are 50 adapted to be sunk to any desired extent within or between guides 13, on which a frame 14 is movable to vertically adjust cutting members 15. These members 15 are shown as two in number and as movable in 55 the direction of the width of these blades and within which is adapted to operate suction apparatus of any desired type for excavating purposes, and shown for purpose of illustration as consisting of tubes 16. 60 Immediately back of these tubes 16 in the line of movement is shown concrete laying apparatus consisting of tubes 17. In this embodiment seen in Fig. 6, I have shown the floats 12 as carrying a separate forming 65

member or mold 18, 19 designates a hydraulic piston which provides for adjustment of the height of the cutting members and the excavating and filling means carried thereby or associated therewith. Guides 20 may also be employed, if desired, the same being illustrated as consisting of sheet piling, but floatable and sinkable alining members, as here illustrated, are also adapted therefor.

In Figs. 6 and 8 I have illustrated methods and apparatus for constructing continuous walls of predetermined height or foundations for other purposes preferably 15 subaqueous but not necessarily so, by means of spaced sheet piling, tubular piling side by side and juxtaposed, or other hollow structures in which successive pairs or mating sections are sunk, hydraulically or otherwise 20 excavated and subsequently filled with concrete, the piling being removed to allow contact and joining of the soft concrete, when the required filling has been attained.

21 designates such tubular piling as seen 25 in Fig. 7 of preferably rectangular section outwardly, and with a cutting face 22 and a guide 23. The piles may interlock to insure close union or alinement but in Fig. 7 I have shown two parallel rows. In Fig. 6, 24 30 designates two rows of sheet piling spaced laterally and formed in a temporary section for excavating and filling purposes by structural shapes or fillers, here shown, as at 25, it being understood that any trans- 35 verse member would also answer this purpose. 26 designates interior longitudinal reinforcements shown in the present instance as consisting of interlocking metal piles.

40 The different molds shown in the various embodiments of my invention may be provided, if desired, with a wearing plate 27 or side sheathing which is replaceable when worn out or when a sheathing of a different 45 character is desired.

The constructions illustrated in Figs. 6 and 8 could, of course, be used between the plates 15, seen in Fig. 7.

In Fig. 9, I have shown a pair of walls, 50 28 and 29, which are formed by the construction seen in Figs. 10 and 11 respectively, and referring now more particularly to said figures, 30 designates conveyers or mechanical excavators, and 31 designates 55 fluid excavators in line with channel ways 32 for the concrete, and I also preferably provide a trailer or former 33 for limiting, leveling and receiving the concrete as the structure is moved forward either continuously or step by step to cut and concrete a 60 channel or any desired number of such channels.

Referring first to the operation of the construction seen in Fig. 1, it will be seen 65 that the channel is preferably first dredged

partly or entirely to the desired depth, although, as is apparent, the floatable mold 1 may be employed for this purpose to any desired extent. A floatable support 1 is then floated into position and sunk in any desired manner in alined position over the dredged or graded channel, preferably by varying the ballast in the float. The mold is then brought to the desired level by suction dredging through the passageways provided therefor, after which the concrete is discharged through passageways by any suitable conduits leading thereto from the concrete receiving or mixing organs, until a desired height and form of concrete is established on the bed. Where the concrete is to extend above the foundation part, as in Fig. 3, the mold preferably remains in sunken position until the concrete is sufficiently set to maintain formation, and if desired, a longitudinal movement may be imparted to the mold by varying the ballast and moving the same along the line of work, or if desired, it may be floated entirely clear of the work.

In the operation of the embodiment seen in Fig. 6, parallel rows of sheet piling 24 are driven down preferably interlocking with each other to form a series of cellular piles in conjunction with the fillers 25. The 90 cells formed by the piling are designed to be progressively dredged and progressively filled with concrete which may be reinforced, as desired. The piles are withdrawn before the concrete is set, thereby leaving a 95 continuous wall of concrete, the upper surface of which may terminate at any desired height, preferably at the surface of the bed of the waterway or the surface of the land. If so used, the earth walls provide 100 support for the soft concrete, as the piles are withdrawn. The operation of the embodiment seen in Fig. 8 is similar to that 105 already described with reference to Fig. 6, except that I have shown tubular piles as 110 being employed, which are in close contact with each other and provide for the excavation and establishment of a continuous concrete wall, the suction dredging being done through the tubes and the concrete being 115 laid through the tubes, and the tubular piles are progressively withdrawn as the work proceeds, thereby providing for the continuous operations of pile driving, suction dredging, concrete placing, for the reinforcement of any desired area of bed. In 120 the operation of the embodiment seen in Fig. 7, the bed is primarily dredged or is dredged through the floatable forms 12 in a manner similar to that described with reference to Fig. 1. The floatable forms 12 and 18 are lowered into alined position and the space between the cutting members 15 is excavated by means of the excavator 16, and as the work proceeds, the excavated 125 130

space in rear of the excavator is filled with concrete through the conduit 17 to a desired height. The molds are advanced along the work as the work progresses, and the cutting plates 15 are raised or lowered by the hydraulic pump 19, as occasion requires. The floatability of the members 12 and 18 may be varied in a similar manner to that already described with reference to Fig. 1.

10 The floatable supports seen in Fig. 1 may be operated in conjunction with one or more of the floats 12 and may be substituted for the intermediate form 18, as is evident.

Referring now to Figs. 10 and 11, a floatable support is shown similar to the other floats already described and capable of being sunk and lowered in the manner already described, being provided with conduits whereby the bed may be dredged and balanced or leveled as desired. In this embodiment, I first employ a mechanical excavator which is followed up by a fluid excavator in rear of which the concrete is laid as the work progresses, and the trailer 25 33 will maintain the height of the wall thus formed at any desired level. The concrete preferably does not extend much above the bed, as the earth forms a support for the soft concrete as the piles are withdrawn therefrom.

It will be obvious from the drawings that simultaneously with the excavating of the bed, the concrete is poured into the place excavated, so that the excavating and the forming of the channel and the laying of the concrete proceeds simultaneously.

It will be apparent that the several means disclosed for carrying out the purposes indicated are simply shown to illustrate one

manner of carrying out my invention in practice and that other methods of construction are practicable without departing from the spirit and scope of my present invention.

Having thus described my invention, what I claim as new and desire to secure by Letters Patent, is:—

1. The method of forming a concrete construction within and upon a subaqueous bed, which consists in supporting upon a float an excavator and concrete filling mechanism, advancing the float to progressively form an excavation in the earth bed and to lay the concrete in the excavated space, floating a mold above a reinforced earth bed, sinking it into working contact therewith, placing concrete upon the reinforced earth bed, and molding the concrete by the contour of the mold.

2. The method of forming concrete within and upon a subaqueous bed, which consists in floating an excavator and concrete laying mechanism into position, adjusting it to the required depth for cutting into the earth bed and laying the concrete therein, operating the excavator and concrete laying mechanism at the same time they are advanced and in the order mentioned to progressively cut the bed and lay the concrete, floating a mold over a reinforced bed to chamber it, placing concrete in the chamber thus formed, and molding the concrete by the contour of the mold.

JOSEPH STOKES WILLIAMS
